CAM GRINDING APPARATUS

Clarence J. Green, Worcester, Mass., assignor to
 Norton Company, Worcester, Mass., a corporation of Massachusetts

Application March 10, 1936, Serial No. 68,864

8 Claims. (Cl. 51—101)

This invention relates to grinding machines, and more particularly to a size controlling apparatus for a cam grinding machine.

One object of this invention is to provide a simple, thoroughly practical size controlling device for controlling the feeding movement of a grinding wheel in a cam grinding machine. Another object of this invention is to provide an electrically controlled sizing apparatus for a camshaft grinding machine which serves to electrically control the feeding movement of the grinding wheel.

Another object of this invention is to provide a work size controlling apparatus for a cam grinding machine which is automatically moved into an operative position before the cam has been ground and automatically removed to an inoperative position after the completion of a grinding operation. A further object of this invention is to provide a sizing device for a cam grinding machine which is automatically moved to and from an operating position in timed relation with the wheel feeding movement.

A further object is to provide such a mechanism in which a fluid pressure actuated means is provided to move the sizing head to and from an operative position. Other objects will be in part obvious or in part pointed out hereinafter.

This invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

Fig. 1 is a fragmentary perspective view together with a wiring diagram of an improved cam grinding machine embodying the size controlling device;

Fig. 2 is a fragmentary cross sectional view, on an enlarged scale, showing the electrical size control unit in side elevation;

Fig. 3 is a fragmentary plan view of the parts shown in Fig. 2; and

Fig. 4 is a longitudinal vertical section, on an enlarged scale, taken through the fluid pressure control valve shown in Fig. 1.

A cam grinding machine has been illustrated in the drawings having a base 11 carrying a wheel slide 12 on which a grinding wheel 13 is rotatably supported. A longitudinally movable table 15 is supported on the front portion of the base 11 and is adapted for a longitudinal traversing movement

on the machine base 11 by means of a manually operable hand wheel 16 which is fixed on the outer end of a shaft 17. The inner end of the shaft 17 carries a gear 18 meshing with a rack bar 19 depending from the under side of the work supporting table 15. These parts are old and well known features of a grinding machine and consequently have not been shown in detail. The grinding wheel 13 and the wheel slide 12 may be fed toward and from the work supporting table 15 by a suitable feeding mechanism, such as for example that shown in the prior United States patent to Cole and Belden No. 1,911,552 dated May 30, 1933.

In order that work of irregular cross section, such as a cam, may be ground, a mechanism may be utilized whereby the work axis and the grinding wheel axis may be moved relative to the other during the grinding operation to generate a desired contour upon the work blank. In the preferred construction, however, the work supporting mechanism is mounted so that it may rock toward and from the operative face of the grinding wheel to produce the desired contour upon the camshaft to be ground. As shown in the drawings, a rock bar 25 is provided with trunnions 26 and 27 which extend from opposite ends of the rock bar 25 and are supported in brackets 28 (Fig. 2) on the table 15. The bracket for supporting the left-hand end trunnions 26, as shown in Fig. 1, is substantially identical to the bracket 28 shown in Fig. 2. These brackets are held in a fixed position on the table 15 by screws 29 and 30. A headstock member 32 and a footstock member 33 may be adjustably supported on the rock bar 25. However, in the form illustrated they are formed integral with the rock bar 25. The head and footstock are provided with work supporting centers 34 and 35 respectively to rotatably support the work piece or camshaft 36 during the grinding operation. The headstock 32 carries a driving member 37 adapted to engage a driving dog 38 which is clamped to one end of the camshaft 36.

A master cam and a follower are arranged to transmit a rocking motion to the camshaft 36 to cause a movement toward and from the grinding wheel and produce the desired contour. As illustrated, a master camshaft 41 is rotatably mounted on the headstock 32 in axial alignment with the camshaft 36 to be ground. The master camshaft 41 comprises a plurality of master cams 42 which are shaped and timed to correspond with the cams to be produced on the finished camshaft. In order that the rotation may rock the bar 25, a bracket 55

member (not shown) is clamped on the table 15 and is arranged to support a rotatable master cam roller or follower 46. The follower 46 is slidably keyed to the rotatable shaft 47 which is rotatably supported in bearings (not shown). From this construction, it will be readily apparent that rotation of the master cams 42, which are in alignment with the camshaft 36, against the master cam roller 46 will cause a rocking motion of the rack bar 25 determined by the shape of the master cam 42, thereby moving the camshaft being ground toward and from the grinding wheel axis to grind the cam blank to the desired contour.

A driving mechanism may be utilized to rotate 15 the master camshaft and the product camshaft to be ground, such as for example that shown in the prior United States patent to Trefethen and Belden No. 1,783,755 dated December 2, 1930.

A mechanism is provided to yieldably maintain 20 the master cam 42 in contact with the periphery of the master cam roller 46. As shown in the drawings, the rock bar 25 is provided with a projecting arm 60. The lower end of a piston rod 61 is pivotally connected by means of a pin 62 to the outer end of the arm 60 and is slidably supported within a cylinder 67. The cylinder 67 slidably supports a piston 68 which is connected to the upper end of the piston rod 61. A spring 69 surrounds the piston rod 61 and is interposed 25 between the piston 68 and a cylinder head enclosing the lower end of the cylinder 67. The spring 69 serves to rock the arm 60 and rock bar 25 in a clockwise direction, as shown in Fig. 1, so as to hold the master cam 42 in operative contact with the master cam roller 46 during the grinding operation and thereby transmits the desired motion to the product camshaft 36 to grind a predetermined contour on the cam being ground. In order to take care of the swinging movement of 30 the arm 60 and piston rod 61, the cylinder 67 is preferably supported by a circular clamping band 70 which is pivotally connected by a stud 71 with a fixed bracket 72.

A suitable driving mechanism may be utilized 45 to rotate the master camshaft to be ground, such for example that shown in the U. S. patent to Trefethen and Belden No. 1,783,755 dated December 2, 1930. This feature is not considered to be a part of the present invention and, therefore, has 50 not been illustrated in detail. For details of the driving mechanism for rotating the master camshaft, reference may be had to the above-mentioned prior patent.

In order that the master cam 42 may be withdrawn from engagement with the follower roller 46 to permit the follower to be shifted into alignment with the next master cam, a mechanism may be utilized to rock the bar 25 against the tension of the spring 69. In the preferred construction, a device operated by fluid pressure is provided, which includes a cylinder chamber 75 formed in the upper portion of the cylinder 67 carrying the piston 68 slidably mounted therein. When fluid under pressure is admitted into cylinder chamber 75, through a port 77 in a cylinder head 78, the piston 68 is forced downwardly against the tension of the spring 69 to rock the bar 25 and withdraw the master cam 42 and the camshaft 36 from contact with the master cam roller 46 and the grinding wheel 13 respectively. After the table 15 has been traversed to bring the next product cam on the camshaft 36 into alignment with the grinding wheel 13, and the master cam roller 46 has been indexed into operative relation with the next master cam, the fluid pressure

within the cylinder chamber 75 is cut off and the released tension of the spring 69 moves the rod 61 upwardly to rock the bar 25 and the master cam 42 and the camshaft 36 into operative contact with the master cam roller 46 and the grinding wheel 13 respectively. 5

As illustrated in the drawings, the wheel slide 12 is provided with a half nut 80 depending from the under side of the slide 12 which engages a rotatable feed screw 81 mounted in suitable bearings (not shown) in the base of the machine. A manually operable hand wheel 82 is mounted on a rotatable shaft 83. The shaft 83 carries a gear 84 meshing with a gear 85 on the end of the feed screw shaft 81. By rotating the hand wheel 82, a rotary motion may be transmitted to the feed screw 81 to cause the grinding wheel 13 to approach or recede from the camshaft 36 to be ground, according to the direction in which the hand wheel 82 is rotated. 10

To operate the fluid pressure mechanism so as to automatically withdraw the cam 42 at the proper time, a valve mechanism operated in timed relation with the moving parts of the grinding machine is provided, and in the preferred construction this valve mechanism is operated in timed relation with the wheel feeding mechanism to rock the bar 25 to an inoperative position when the feed screw 81 is rotated to move the grinding wheel away from the work. As shown 15 in the drawings, the valve mechanism comprises a casing 90 fixed to the base 11. A balanced piston type valve 91 is slidably mounted therein. The extended portion of the piston rod 91 is connected to a link 92. In the operation of the 20 mechanism, it is desirable that the valve operate when the feed wheel 82 is turned in either direction, but this mechanism must be so constructed and arranged that continued movement of the feed mechanism to position the grinding wheel 25 is permissible after the valve has been shifted. To accomplish this, a friction device is provided, as illustrated in Figs. 1 and 4. As illustrated, the link 92 is connected by a pin 93 to a downwardly extending arm 94 of a friction device 95. The friction device comprises two semi-circular shaped members which are adapted to mate with the forwardly extending projection 96 of the feed screw 81. The two halves of the clamping ring are connected by means of bolts 97 and 98 which 30 pass through clearance holes in the projecting lugs 99 and 100 in the upper friction member 101 and through the lugs 102 and 103 in the lower portion of the friction device 95. A pair of springs 104 and 105 surround the projecting ends of the bolts 97 and 98 and serve to yieldingly clamp the members 95 and 101 to the shaft 96. Nuts 106 and 107 are provided on the lower ends of the bolts 97 and 98 and serve to adjust the tension of the springs 104 and 105 so that the members 95 and 101 may be caused to frictionally engage the shaft 96 with the desired tension. 35

It will thus be seen from this construction that the turning of the hand feed wheel 82 is transmitted through the friction device 95, the arm 94, the link 92, to slide the valve stem 91 within the valve casing so as to control the rocking movement of the bar 25. The motion of the valve stem 91 continues until the valve pistons 40 reach the other end of the valve casing 90, after which the feed screw 81 and the shaft 96 extending therefrom are rotated against the friction of the device 95. 45

The valve 90 is of the piston type having valve 50

pistons 110, 111, 112 and 113 formed integrally with the valve stem 91. Fluid under pressure from a source (not shown), such as a pump and reservoir within the base, passes through a pipe 114 into a valve chamber 115. In the position of the valve parts, as illustrated in Figs. 1 and 4, fluid is exhausted from the cylinder chamber 75 through the port 77, a pipe 116, into a passage 117 within the valve casing which opens into a valve chamber 118 between the valve pistons 110 and 111 and out through a pipe 119 into the reservoir. Fluid under pressure from a gauge operating mechanism to be hereinafter described exhausts through a pipe 120 into a passage 121 in the valve casing 90 which enters into a valve chamber 122 between the pistons 111 and 112 and passes outwardly through an exhaust pipe 123 into the reservoir. A throttling valve is provided to control the exhaust of fluid through the pipes 116 and 120. As illustrated, a throttle valve member 124 is provided to control the passage of exhaust fluid through the passage 117 so as to control the rocking movement of the rock bar 25. A valve member 125 serves to throttle the passage of fluid through the passage 121 so as to control the movement of the sizing device to be hereinafter described. The valve stem 91 and the pistons 110, 111, 112 and 113, as shown in Figs. 1 and 4, are in an operating position with the master cam 42 in contact with the master cam roller 46, and the product cam on the shaft 36 is in operative engagement with the grinding wheel 13. When the product cam has been ground to a predetermined size and contour, the feed screw 81 is rotated to remove the grinding wheel from operative contact with the work. During the initial turning of the feed screw 81, the extended portion 96 is rotated to rock the friction device 95, the link 92 and to move the valve stem 91 toward the left, as viewed in Figs. 1 and 4. This movement shifts the valve piston 112 toward the left, which serves to open the passage 121 to the chamber 115 so as to admit fluid under pressure to operate the sizing device to be hereinafter described and continued movement of the valve serves to open the passage 117 to the valve chamber 115 so as to admit fluid under pressure through the pipe 116, port 77, into cylinder chamber 75 to rock the bar 25 in a counterclockwise direction, as shown in Fig. 1, to remove the master cam 42 and the product camshaft 36 to an inoperative position out of contact with the master cam roller 46 and the grinding wheel 13 respectively.

In order that the feed screw may be turned automatically to move the wheel slide 12 in either direction toward or from the camshaft 36, a power driven mechanism is provided which includes a pulley 130 driven by a belt 131 from a suitable source of power. The pulley 130 is fixedly mounted on a rotatable shaft 132 which is supported in bearings (not shown) in the base 11 of the machine. The shaft 132 is provided with a worm 133 meshing with a gear 134 journaled on a transverse shaft 135. Power may be transmitted from the gear 134 to rotate the feed screw 81 by a direct driving connection but in the preferred construction a tumbler gear 136 is mounted upon a swinging arm 137 which is pivotally supported to swing about the shaft 135 as a pivot. The gear 136 in turn meshes with a gear 138 journaled on the shaft 135 and secured to the gear 134 so that as power is applied to the pulley 130, the gear 138 transmits power to the tumbler gear 136 in all positions of the arms 137.

A lever 140 is fixed on the outer end of the shaft 135 to turn the arm 137 and hence to permit manual control of the tumbler gear 136. By movement of the lever 140 toward the left, as viewed in Fig. 1, said tumbler gear 136 is thrown into mesh with the gear 85 on the outer end of the feed screw 81, thereby causing a rotation of the feed screw in the direction to feed the grinding wheel 13 toward the camshaft 36. A spring pressed plunger 141 is mounted on the front of the machine base and contacts with a projection on the rear of the lever 140 and serves to hold the lever in its operative position with the tumbler gear 136 in mesh with the gear 85 to cause an infeeding movement of the grinding wheel 13.

To obtain a reverse feed, that is to move the grinding wheel rearwardly, after the grinding operation has been completed, a mechanism is provided for rotating the feed screw by power in the opposite direction to move the grinding wheel 13 rearwardly, preferably at a higher rate of speed than that at which it moves forwardly in its grinding feed movement. To accomplish this, a gear 145 is mounted on the shaft 135 to be driven by power imparted to the gear 134, and said gear 145 meshes with a gear 146 on a shaft 147. The shaft 147 also carries a gear 148 which is formed either integral with or fixed to the gear 146. A gear 150 is mounted on the feed screw 81 and meshes with a tumbler gear 151 which is rotatably supported on a stud 152 carried by a bell crank lever 153. The bell crank lever 153 is pivoted to swing upon a portion of the feed screw shaft 86 so that it may be moved to roll the gear 151 into mesh with the gear 148 on the shaft 147. It will be noted that the gears 146 and 148 constitute intermediate gears to give a reversal in direction of rotation to the feed screw 81. It will be readily seen from the construction described that by throwing the gear 136 into mesh with the gear 85, a slow forward infeeding movement of the grinding wheel 13 toward the camshaft 36 is obtained and that by rolling the tumbler gear 151 into mesh with the intermediate gear 148, a rapid reverse or rearward feed is produced to move the grinding wheel 13 rapidly away from the camshaft 36 to an inoperative position.

Automatic means for controlling the feeding mechanism in grinding successive cam blanks on an integral camshaft to a predetermined contour and size will now be described. This includes a caliper device arranged to contact with the cam being ground during the grinding operation and also a mechanism responsive to the action of the caliper device after the grinding operation has progressed and the cam being ground has been reduced to a predetermined contour and size. The caliper device may be combined with a steadyrest or mounted on a fixed part of the machine or work table but, as illustrated, it has been shown as mounted on a bracket 160 which is fixed to the base 11 by screws 161 and 162. A caliper head 163 is pivotally supported on the bracket 160 by means of the pivot pin or trunnion 164. The sizing head 163 comprises a pair of upwardly extending arms 165 and 166 which slidably support a plunger 167. The plunger 167 carries at its outer end a roller 168 supported by a stud 169. The roller 168 is preferably supported in a slotted end portion in the plunger 167 and is arranged to engage the periphery of a cam being ground on the camshaft 36 during the grinding operation.

The contact roller 168 is maintained in operative contact with the cam being ground by means of a spring 170 which surrounds the plunger 167 and is interposed between the arm 166 and an 5 adjustable collar 171 which is adjustably supported on a threaded portion 172 on the plunger 167. By adjusting the collar 171 relative to the plunger 167, the tension of the spring 170 may be adjusted to maintain the contact roller 168 in 10 engagement with the cam being ground at the desired pressure.

The caliper device preferably operates a pair of contact members, one acting to terminate the power infeed of the grinding wheel and 15 permit the finish grinding operation to take place while the grinding wheel slide remains stationary; and the second contact members operating to initiate a reverse feed in which the grinding wheel is rapidly removed from engagement with the work.

The upper end of the arm 165 is provided with a block 175 of insulating material. The block 175 carries a pivot pin 176 which supports a pair of pivotally mounted contact members 177 and 25 178. The contact members 177 and 178 have a downwardly projecting arm 179 which is arranged in the path of the adjustable collar 171. A spring 180 is interposed between the downwardly extending arms 179 on each of the contact members 177 and 178 and the arm 165 normally tends to rock the contact arms 177 and 178 in a counterclockwise direction (Fig. 2). The contact member 177 is connected by a wire 185 with a binding post 186 and the contact member 178 is connected by a wire 187 with a binding post 188. The binding posts 186 and 188 serve to connect the sizing head with the wheel feed operating mechanism.

The arm 166 is provided with an insulating block 190 at its upper end which is provided with a pair of adjustable contact screws 191 and 192 which cooperates with the pivotally mounted contact members 177 and 178 respectively. Each of the contact screws 191 and 192 are connected by a single contact member 193 with a binding post 194. The upper portion of the pivoted contact arm 177 is preferably formed as a flat spring member which supports the contact point 177.

In the operation of this sizing device, the grinding of the cam proceeds until the adjustable collar 171 engages the arm 179 to rock the contact member 177 into engagement with the adjustable contact screw 191, serving to make the first contact which is connected in a manner to be hereinafter described to stop the infeeding movement of the grinding wheel but allowing the wheel to remain in operative contact with the cam being ground to finish grind the same. The grinding operation on the cam blank continues and the adjustable collar 171 moves toward the left, as viewed in Fig. 2, as permitted by a reduction in size of the cam, flexing the spring 178 which carries the contact member 177 until the adjustable collar 171 engages the arm 179 at the lower end of the contact arm 178 and swings the contact 178 into engagement with the contact at the end of the adjustable screw 192 which serves in a manner to be hereinafter described to cause a rapid rearward movement of the grinding wheel.

The sizing head is preferably operated on a low voltage or low energy current in a manner similar to that shown in the prior patent to Cole and Belden No. 1,911,552. In the preferred construction, a battery 200 serves to supply current which

is connected to be controlled by the caliper head 163. One terminal of the battery 200 is connected by means of a knife switch 201 and a wire 202 with the binding post 194 which is connected to both of the adjustable screw contact members 191 and 192. The other terminal of the battery 200 is connected to a relay 203 and a relay 204. An electromagnet 205 of the relay 203 is connected in series by a wire 206 with the binding post 186, and an electromagnet 207 of the relay 204 is connected in series by a wire 208 with the binding post 188 on the side head 163.

To facilitate loading of the machine as well as indexing the table 15 and camshaft 36 and master cam 42 longitudinally to grind successive cams on the camshaft 36, it is desirable to provide a means for swinging the sizing head to an inoperative position during the indexing and loading periods. The sizing head 163 is pivotally mounted on a stud 164 which is supported in the bracket 160 fixed to the base of the machine. An adjustable stop screw 210 serves to locate the sizing head in an operating position so that the axis of the pin 169, the axis of the work piece 36 and the axis of the grinding wheel lie in the same horizontal plane. In order quickly to remove the sizing head 163 to an inoperative position, a fluid pressure mechanism is provided which is preferably operated in timed relationship with the wheel feeding movement. This mechanism may comprise a fluid pressure cylinder 211 which is fixed to the bracket 160. The cylinder 211 contains a piston 212 which is mounted on the lower end of a piston rod 213. The upper end of the piston rod is connected by a stud 214 with an arm 215 projecting from the sizing head 163. The gauging head is yieldingly held in an operating position by means of a spring 216 which surrounds the piston rod 213 and is interposed between a collar 217 and the upper surface of a cylinder head 218. The spring 216 serves to rock the gauging head in a counterclockwise direction into the position illustrated in Fig. 2.

When the feed screw 51 is turned to cause a rearward feeding movement of the grinding wheel 13, the valve piston 91 is moved toward the left, as viewed in Figs. 1 and 4, as above described, serving to admit fluid under pressure through a pipe 120 into a cylinder chamber 219 to cause a downward movement of the piston 212. The downward movement of the piston 212 serves to cause the pivot 164 to ride within an elongated slot 220 in the bracket 160 until the pivot pin 164 engages the lower surface of the elongated slot, and continued movement 55 serves to further rock the sizing head 163 in a clockwise direction into a dotted line position, as indicated in Fig. 2, so that the contact roller 168 is moved into an inoperative position 168a a sufficient distance from the cams on the camshaft so that the shaft may be readily indexed into the next operating position or so that the finish ground camshaft may be readily removed without interference on the part of the size head.

In the operation of this sizing apparatus on a cam grinding machine, a camshaft 36 to be ground is placed on centers 34 and 35 with the driving dog 38 engaging the driver 31. The camshaft and master camshaft 41 are then rotated and the lever 140 is moved toward the left into the position as viewed in Fig. 1, to throw the tumbler gear 136 into mesh with the gear 85 mounted on the shaft 96 which extends from the feed screw 81 so as to start an infeeding movement of the grinding wheel slide 12 and the grind-

ing wheel 13. This movement serves through the gear 84 and shaft 83 to rotate the hand wheel 82 which in turn rotates a friction disk 227 to close a knife switch 201, as is more fully described in the above-mentioned U. S. patent to Cole and Belden No. 1,911,552. When the infeeding movement starts, the friction device 85 moves the link 92 and valve stem 91 toward the left (Figs. 1 and 4), until the valve pistons 110, 111, 112 and 113 assume the positions illustrated in Figs. 1 and 4. This movement allows fluid within the cylinder chamber 75 to exhaust and allows the released tension of the spring 69 to rock the bar 25 into operative position with the master cam 42 in contact with the follower roller 46 and the cam to be ground in operative position with relation to the grinding wheel 13. At the same time, fluid under pressure is allowed to exhaust from the cylinder chamber 219, releasing the tension of the spring 216, which rocks the sizing head 163 in a counterclockwise direction (Fig. 2) into the full line position, as indicated in Fig. 2, so that the feeler roller 168 is in operative contact with the cam being ground. The infeeding movement of the grinding wheel 13 continues until the adjustable collar 171 engages the arm 179 to rock the contact member 177 into engagement with the adjustable contact member 191. The closing of contacts 177 and 191 serves to close a circuit and through the wire 206 to energize the magnet 205 on relay 203 so as to close a circuit between the high voltage lines 221 and 222 to energize a solenoid 225 which serves to move the lever 140 toward the right, as viewed in Fig. 1, to throw the tumbler gear 136 out of mesh with the gear 85 on the feed screw shaft 96, thereby stopping the infeed of the grinding wheel 13, but allowing the wheels to remain in grinding contact with the work to allow the wheel to spark-out or finish grind the cam being ground. The grinding continues and the roller 168 advances toward the work axis as the cam is reduced in size. The adjustable collar 171 continues to rock the arm 179, flexing the contact spring 177 until the collar 171 engages and rocks the contact member 178 through a sufficient extent so that it engages the adjustable contact screw 192. Closing of the circuit by contacting of the member 178 and the contact screw 192 serves to energize the electromagnet 207 of the relay 204 which in turn makes a circuit between the higher voltage or higher energy circuit indicated by the wires 221 and 222 to energize a solenoid 226 which serves to rock a lever 223 in a counterclockwise direction against the tension of a spring 226, thereby rocking the bell crank 153 in a counterclockwise direction to rock the reverse tumbler gear 151 into engagement with the gear 148 to cause a rapid reverse movement of the feed screw 81 to rapidly move the wheel slide 12 and grinding wheel 13 to an inoperative position. During the rearward movement of the slide, the shaft 83 is rotated in a reverse direction by means of the gear 84, causing the friction plate 227 to rotate until the abutment 221 engages and opens the knife switch 201 to break the low voltage current from the battery 200 and thereby render the sizing head inoperative until the knife switch 201 is again closed at the start of the next grinding operation.

During the initial reverse movement of the feed screw 81 and its projecting shaft 96, the link 92 and valve piston 91 are moved toward the right, as viewed in Figs. 1 and 4, so as to admit fluid

under pressure from the pipe line 114 first through the pipe 126 into the cylinder chamber 219 to rock the sizing head 163 to an inoperative position, as indicated in broken lines in Fig. 2, and then to admit fluid under pressure through the pipe 116 into the cylinder chamber 75 to cause the rock bar 25 to rock in a counterclockwise direction (Fig. 1), to separate the master cam 42 from the master cam roller 46 and to remove the cam being ground on the camshaft 36 from operative engagement with the grinding wheel 13. The table 15 may then be indexed longitudinally to bring the next cam blank into operative engagement with the grinding wheel, and the cycle of grinding is then completed. This cycle of operation is continued until all of the cams on the shaft have been ground to a predetermined size and contour, after which the camshaft 36 may be removed and a new camshaft mounted in place for a grinding operation.

It will thus be seen that there has been provided by this invention apparatus in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

I claim:—

1. A sizing device for a cam grinding machine comprising a sizing head having a movable contact member arranged to continuously engage the periphery of a cam during the grinding operation, an adjustable member moved by said contact member, a pair of adjustable electrical contacts carried by said head and actuated by said contact member after the cam has been ground to a predetermined extent to stop the infeed of the grinding wheel, and means including a second pair of electrical contacts carried by said head and arranged to reverse the wheel feeding movement when the cam has been finish ground to a predetermined size and contour.

2. A sizing apparatus for a cam grinding machine comprising a movable sizing head, a movable contact member mounted on said head and yieldingly maintained in contact with the periphery of said cam during grinding, means including a pair of electrical contacts on said head which are actuated by said movable contact member when the cam has been ground to a predetermined extent to stop the infeed of the grinding wheel, and means including a second pair of electrical contacts on said head which are actuated by movement of said contact member to cause a rearward movement of the grinding wheel when the cam has been ground to a predetermined size and contour.

3. A cam grinding apparatus comprising a rotatable grinding wheel, a rotatable work support, a reversible feeding mechanism for feeding the grinding wheel and work support relatively toward and from each other to grind a cam blank to a predetermined size, means including a master cam and follower to move the grinding wheel and work support transversely and relatively toward and from each other during the grinding operation to grind the cam blank to a predetermined contour, a sizing device including a movable feeler which continuously engages the

periphery of the cam being ground during grinding to automatically control said feeding mechanism, a pair of adjustable electrical contacts actuated by said feeler to stop the transverse feeding movement between the wheel and work after the cam has been ground to a predetermined extent, and means including a second pair of electrical contacts actuated by said feeler to reverse the feeding mechanism when the cam has been ground to a predetermined size and contour.

4. A cam grinding apparatus comprising a rotatable grinding wheel, a work support, a reversible feeding mechanism for feeding the grinding wheel toward and from the work, means including a master cam and roller to move the work support toward and from the grinding wheel to grind a cam blank to a predetermined contour, a sizing device including a movable feeler which continuously engages the periphery of the cam being ground during grinding to automatically control said feeding mechanism so as to grind successive cam blanks to a predetermined size, and automatic means operated in timed relation with the rearward movement of the grinding wheel to move the sizing device to an inoperative position so as to permit a traversing movement of the work support to present the next cam into operative relation with the grinding wheel.

5. A cam grinding apparatus comprising a rotatable grinding wheel, a work support, a feeding mechanism for feeding the grinding wheel toward and from the work, means including a master cam and roller to move the work support toward and from the grinding wheel to grind a cam blank to a predetermined contour, a sizing device including a movable feeler which continuously engages the periphery of the cam being ground during grinding to automatically control said feeding mechanism, and automatic means operated in timed relation with the forward feeding movement of the grinding wheel to move the sizing device into an operative position with the feeler in contact with the cam and operated in timed relation with the rearward movement of the grinding wheel after a grinding operation to move the sizing device to an inoperative position so as to permit a traversing movement of the work support to present the next cam into operative relation with the grinding wheel.

6. A cam grinding apparatus comprising a rotatable grinding wheel, a work support, a feeding mechanism for feeding the grinding wheel toward and from the work, means including a

master cam and roller to move the work support toward and from the grinding wheel to grind a cam blank to a predetermined contour, a sizing device including a movable feeler which continuously engages the periphery of the cam being ground during grinding to automatically control the size of said cam, and means operated in timed relation with the wheel feeding movement to move said master cam into operative relation with the master cam roller and to move the sizing device so that the contact member engages the periphery of the cam being ground.

7. A cam grinding apparatus comprising a rotatable grinding wheel, a work support, a feeding mechanism for feeding the grinding wheel toward and from the work, means including a master cam and roller to move the work support toward and from the grinding wheel to grind a cam blank to a predetermined contour, a sizing device including a movable feeler which continuously engages the periphery of the cam being ground during grinding to automatically control the cam size, and automatic means operated in timed relation with the rearward movement of the grinding wheel to separate the master cam from the roller and to move the sizing device to an inoperative position so as to facilitate a traversing movement of the work support to present the next master cam into operative relation with the grinding wheel.

8. A cam grinding machine comprising a rotatable grinding wheel, a work support movable toward and from the grinding wheel, means for feeding the grinding wheel toward and from the work support, means for supporting a camshaft on said support in operative relation with the grinding wheel, means including a set of master cams and a cam follower arranged to move the support toward and from the grinding wheel to cause the latter to grind a predetermined contour on the cam blanks, means for traversing the work support and the grinding wheel longitudinally relative to each other, a movable sizing device having a movable feeler or contact member which continuously engages the periphery of a cam during the grinding operation to control said feeding mechanism, means operated by the rearward movement of the wheel to move the master cam away from the follower, and means associated therewith to move the sizing device to an inoperative position to permit either a traversing movement of the camshaft or a removal of the same after the last cam has been ground.
